UNITED STATES PATENT OFFICE.

DAVID JENKINS, OF SHEBOYGAN, WISCONSIN, ASSIGNOR TO THE JENKINS MACHINE COMPANY, OF SAME PLACE.

WOOD-BENDING PRESS.

SPECIFICATION forming part of Letters Patent No. 437,904, dated October 7, 1890.

Application filed February 7, 1890. Serial No. 339,572. (No model.)

To all whom it may concern:

Be it known that I, DAVID JENKINS, of Sheboygan, in the county of Sheboygan, and in the State of Wisconsin, have invented certain new and useful Improvements in Wood-Bending Presses; and I do hereby declare that the following is a full, clear, and exact description thereof.

My invention relates to wood - bending presses; and it consists in certain peculiarities of construction and combination of parts, to be hereinafter described with reference to the accompanying drawings, and subsequently claimed.

15 In the drawings, Figure 1 represents a side elevation of a bending-press constructed according to my invention; Fig. 2, a front elevation of the same with parts broken away; Fig. 3, a vertical longitudinal section of the 20 press; and Fig. 4, a horizontal section illustrating the valve-gear of a steam-cylinder that forms part of said press.

25 Referring by letter to the drawings, A represents standards for the support of a shell B, that forms the bed of the press and is concave upon its upper face. At its front end the shell B is provided with ears b, having vertical slots c, and a rod C is passed through these slots, and similar ones d, in ears e, belonging to another hollow shell D, that forms 30 the platen of the press, the latter shell being convex upon its under face. Both of the shells B D are connected by pipes E with a source of steam-supply, (not shown,) and thus 35 said shells are made hot, in order to dry up the moisture in the wood subjected to the action of the press, the fibers in said wood being fixed by combined heat and pressure, as is usual in the art to which my invention relates.

40 At about midway of its length the sides of the shell B are provided with lugs F, having vertical screw-threaded openings for engagement with the screw-threaded ends f of arms G, that are coupled to a transverse rod H, and by means of nuts g on said arms above and below the lugs the rod may be raised and lowered, for the purpose to be hereinafter described.

45 50 Loose on the rod H, between rigid collars

h, is a sleeve I, provided with arms J, that connect at their lower ends with links J', that are in turn connected to a cross head K on the rod L of a piston M, the latter being arranged in a cylinder N, that is supported on 55 brackets h', connected to the upper face of the shell D, as best illustrated in Fig. 3. Near the sleeve I the arms J are provided with ears i, these ears being connected to a bracket P on the upper face of the shell D by means of 60 links Q, and secured to the front of said shell is a bracket R, that serves as a guide for the piston-rod above-described.

The steam-cylinder N is provided with inlet-ports j k and an exhaust-port m, leading 65 from a steam chest S, that forms part of said cylinder, the steam-chest being connected to the shell D by means of a pipe T. Arranged within the steam-chest is a valve U, having flanges n o for controlling the inlet-ports j k 70 and a bridge p for controlling the exhaust-port m, the valve being also provided with two lugs q, between which is arranged a disk V, having a wrist-pin r, connected to a lever W, and by the latter mechanism said valve 75 is reciprocated to open and close said ports. While I have described an eccentric mechanism for actuating the slide-valve U, I do not wish to be understood as limiting myself thereto, as other well-known means may be 80 as readily employed for the same purpose.

The rear end of the shell B is preferably provided with a vertical guide s, that comes between lugs t t on the adjacent end of the shell D, and I prefer to provide the steam- 85 cylinder with a cock u for the purpose of draining off the water of condensation that may accumulate therein.

In describing the operation of my device I will assume that sufficient steam has been admitted to the cylinder N to force the piston M its full throw toward the front and that the several parts stand in the position shown by Fig. 3. The material to be bent is placed on the concave face of the shell D, and steam 90 being cut off from the cylinder-ports the shell B will gradually descend as the steam back of the piston M is condensed. Now as the shell B descends it draws on the links Q, and thereby actuates the arms J and links J' to 100

move the rod N and said piston to the rear, the leverage increasing as said shell continues its descent. When the descent of the shell B is nearly accomplished, the lever W is actuated to move the valve U, so as to open the inlet-port k to live steam, and thus said shell is forced down and held by great pressure against the material to be bent. The bending and drying of the wood being accomplished, the valve U is shifted to cut off live steam from the port k and permit it to enter the port j, whereby the shell B is raised to its former position by the pressure against the piston M, the dead steam in the cylinder N being exhausted through the ports k m, it being understood that a movement of said valve to open either of the ports j k will at the same time open the port m in the same proportion, the valve being so constructed that when one inlet-port is open to live steam the other inlet-port is in communication with the exhaust-port.

By having the rod H vertically adjustable, as above described, the shell may be positively adjusted in proportion as the material to be bent varies in thickness, the slotted ears on said shell and on the one D permitting the forward end of the former shell to raise or lower when the adjustment is being effected.

Having thus described my invention, what I claim as new, and desire to secure by Letters Patent, is—

1. In a wood-bending press, the combination of the bed, a transverse rod connected to said bed, a sleeve loose on the rod and provided with arms having ears arranged near the sleeve, a hollow platen linked to the ears of the sleeve-arms and provided with means for connection with a source of steam-supply, a steam cylinder and chest supported on the platen and having a pipe-connection therewith, a piston arranged in the cylinder and provided with a rod, a cross-head and links connecting the piston-rod with said sleeve-arms, and a valve arranged in the steam-chest to govern the admission of steam to said cylinder, substantially as set forth.

2. In a wood-bending press, the combination of the bed, a vertically-adjustable transverse rod connected to said bed, a hollow platen provided with means for connection with a source of steam-supply, a lever mechanism connecting the rod and platen, a steam cylinder and chest supported on said platen and having a pipe-connection therewith, a piston arranged in the cylinder and provided with a rod connected to the lever mechanism,

and a valve arranged in the steam-chest to govern the admission of steam to said cylinder, substantially as set forth.

3. In a wood-bending press, the combination of the bed, a hollow platen provided at one end with a guide and having means for connection with a source of steam-supply, a rod loose in the guide, a lever mechanism connected to the platen and rod, a steam cylinder and chest supported on said platen and having a pipe-connection therewith, a piston arranged in the cylinder and connected to said rod, and a valve arranged in the steam-chest to govern the admission of steam to said cylinder, substantially as set forth.

4. In a wood-bending press, the combination of a bed and platen, respectively provided at one end with ears having vertically-disposed slots, a rod passed through all the slots, standards adjustably connected to opposite sides of the bed, a transverse rod connecting the standards above said bed, a sleeve loose on the rod, and a lever mechanism connecting the sleeve and platen, substantially as set forth.

5. In a wood-bending press, the bed and platen in the form of shells provided with means for connection with a source of steam-supply, a lever mechanism connected to the platen, a steam cylinder and chest supported on said platen and having a pipe-connection therewith, a piston arranged in the cylinder and provided with a rod connected to the lever mechanism, and a valve arranged in the steam-chest to govern the admission of steam to the cylinder, substantially as set forth.

6. In a wood-bending press having a hollow platen provided with means for connection with a source of steam-supply, a lever mechanism connected to the platen, a steam cylinder and chest supported on said platen and having a pipe-connection therewith, a piston arranged in the cylinder and provided with a rod connected to the lever mechanism, a valve arranged in the steam-chest to control the inlet-ports of the cylinder, and a bridge carried by the valve to control the exhaust-port of said cylinder, substantially as set forth.

In testimony that I claim the foregoing I have hereunto set my hand at Sheboygan, in the county of Sheboygan and State of Wisconsin, in the presence of two witnesses.

DAVID JENKINS.
